UNITED STATES PATENT OFFICE.

WILLIAM A. DAWSON, OF STONY POINT, CALIFORNIA.

OVERALLS.

SPECIFICATION forming part of Letters Patent No. 295,619, dated March 25, 1884.

Application filed December 13, 1883. (No model.)

To all whom it may concern:

Be it known that I, WILLIAM A. DAWSON, of Stony Point, county of Sonoma, State of California, have invented a new and useful 5 Improvement in the Manufacture of Pants and Overalls; and I do hereby declare the following to be a full, clear, and exact description of the same.

My invention relates to the manufacture of pants and overalls, the object being to make them more durable by re-enforcing those parts upon which the greatest amount of strain and wear comes.

In the drawings accompanying this application and forming a part thereof, Figure 1 represents a rear view of the overalls with my improvements. Fig. 2 is a front view of the same; and Fig. 3 represents them as they would appear upon a person in a reclining 20 position, intended to show the formation of the seat of the overalls.

The first improvement which I have made relates to the corners of the pockets, where the strain caused by putting the hands in and 25 out of the pockets is most liable to cause a rupture of the seam or the material of which the article is composed. Numerous devices have been devised for strengthening this part 30 of the overalls; but they are either useless metallic fastenings or costly stitched devices.

My improvement consists in running a coiled stitch at each corner of the pocket, as shown at A in Figs. 1 and 2. This stitch I commence by running a circular stitch across 35 the main seam at each corner of the pockets, and then decreasing the circle toward the center, so as to form a coil, as represented. This seam can be easily sewed by turning the goods under the foot of the sewing-machine, and 40 when completed an extremely strong fastening is formed, as the seam crosses and re-crosses the main seam and forms a net-work of stitches without applying any extraneous devices, such as rivets, gussets, or stays.

Instead of lining the pants throughout, I 45 line only the parts which are subjected to the greatest wear. These parts are the front of the leg, the seat, and the crotch. For the legs I cut a half-lining for the front of each, 50 and place it there, leaving the rear portions unlined. This half-lining can either be at-

tached by means of the side seams, at the same time that the parts of the pants are sewed together, and allowed to be loose from the outer goods, or it can be quilted by sewing one or 55 more rows of stitches along the leg of the pants, as shown in Figs. 2 and 3. I prefer the latter plan, as it gives a better body and causes the goods to last longer. This stitching or quilting may be made in various patterns, so as to give the overalls a neat and corded appearance. This half-lining may extend entirely up to the waistband, or, if preferred, to the top of the leg only, and may be stitched across just below the pockets. When 60 extended to the waistband, I use the inner goods or lining to form the inside flap, C, of the front opening, thus avoiding the necessity of cutting out special pieces to form this part. This is shown in Fig. 2, the seam connecting 65 the inner and outer portions being shown at c. In this case I also use the lining for another purpose—namely, to form the back part of the pocket, it being only necessary to run a row of stitching, d, in the form of a pocket, to secure the two thicknesses together, and then 70 make the opening for the pocket in the outer thickness.

Instead of making a single pocket, as heretofore, I make two pockets on each side of the 75 back by first forming a large pocket, which extends half-way across the overalls on each side, and then running a line of stitches down the center to separate it and divide it into two, as shown in Fig. 1. These pockets are very convenient for workmen, on account of the numerous articles which they are usually compelled to carry, and which very often require to be held in different pockets.

The waistband I make in four separate pieces, 80 1 2 3 4, the piece 1 extending from the front opening to a point over the hip on one side, and the piece 2 upon the other side. The pieces 3 and 4 extend in like manner from over the hip to the middle of the back on each side. The pieces are not stitched out to the ends to 85 the main body of the cloth; but the ends are left unstitched, each part being provided with a buckle on one end and a tab upon the other, so that the meeting ends of each can be buckled 90 together. This construction brings one buckle directly in front, one at each side over the hips,

and another at the back. Under the back buckle I insert a triangular elastic gore, *e*, which will take up the slack made by tightening the waistband. Each waistband-piece has 5 a widened portion, *w*, on its under edge, opposite the corner of each pocket, so that when the waistband is sewed on, this widened portion will extend downward and cross the corner of the pocket. This serves as a stay-piece to 10 strengthen the pocket-corners, and the coiled seams heretofore described may be stitched over this piece. This waistband enables the wearer to tighten the overalls above his hips at four points, and thus avoid puckering the 15 goods at one point, as heretofore. At the same time it makes a comfortable and neat fit, and the front buckle prevents the strain from coming directly upon the buttons in front.

In making the seat of the pants I use a patch 20 or extra seat-piece, *f*, which may be placed either inside or outside. This piece I attach to the pants or overalls by numerous lines of stitches, in the same manner as described for the leg-linings, so as to accomplish more intimate union of the parts than usual, thus giving 25 a thick, firm double seat, which will wear for a long time. Between these two thicknesses of material I make the behind pockets.

For the crotch part of the overalls I use an 30 extra re-enforcing piece, *g*, which can be quilted or remain loose, as found most desirable.

For protecting the crotch-seams I use welt or

stay pieces *h*, which cover the seams, and are stitched to the goods on each side of the seam.

By the means described I strengthen and reinforce the parts most liable to wear, leaving those parts that receive but little wear without lining or extra material, thus providing overalls that will yield a maximum service at the least possible cost.

Having thus described my invention, what I claim as new, and desire to secure by Letters Patent, is—

1. The inside flap, *C*, of the front opening of pants and overalls, formed from the lining 45 thereof, substantially as described.

2. An auxiliary waistband for pants, made in four pieces, and arranged to be connected together by buckles in front, over the hips on each side, and at the back, substantially as and 50 for the purpose described.

3. In combination with overalls or pants having a main waistband, the auxiliary waistband-pieces 1 2 3 4, having widened portions *w*, such widened portions forming an integral 55 part of said waistband, substantially as and for the purpose set forth.

In witness whereof I have hereunto set my hand.

WILLIAM A. DAWSON.
